ADDRESSING MACHINE MASTER

Samuel G. Jackson, Lubbock, Tex.

Application December 21, 1954, Serial No. 476,695

5 Claims. (Cl. 101—149.4)

The present invention relates to an addressing master plate, more particularly, to a paper master for use in the spirit duplication process.

The conventional addressing machine used to address quantities of correspondence employs an addressing master which is used to print the address upon the copy. The addressing machine essentially comprises apparatus for individually moving the addressing master into the proper position, and means for printing the address through a suitable process.

A common type of addressing master comprises a metallic plate on which the address is impressed. There are also numerous addressing machines which employ the spirit duplication principle. In the spirit duplication process the pattern which is to be printed upon the copy is made in ink. Either the copy sheets or the master sheets are moistened with a suitable liquid. The duplicating ink is soluble in that liquid. Consequently, a portion of the ink is transferred in order to make the impression upon each sheet of copy.

While this principle has been employed in addressing machines, there is one inherent handicap. The names and addresses are typed upon a paper master which is in the form of a continuous roll. Consequently, the order of names cannot be readily changed. Neither can names be inserted nor old names taken out as desired. In a business with a mailing list which is constantly changing this handicap is a major disadvantage.

The present invention discloses an addressing machine master which uses the spirit duplicating principle. In this invention each name and address is placed upon a separate master so that it can be treated as a card in a file. These masters are made of such a form that they can be readily fed from a magazine in the addressing machine.

The addressing machine master of this invention essentially comprises a card which has a sheet of carbon paper on one side and a sheet of master duplicating paper on the other side. Both the carbon paper and the duplicating paper are clamped to the card by means of a metallic strip. This strip overhangs each side of the card in order to engage the sides of the magazine accommodating these masters.

It is, therefore, the principal object of this invention to provide an improved addressing machine master.

It is another object of this invention to provide a simple and inexpensive paper master.

It is a further object of this invention to provide a novel form of a paper master having a single name and address thereon and which may be handled individually.

It is a further object of this invention to provide a paper master that can be readily fed from a magazine in the addressing machine.

Other objects and advantages of this invention will become apparent upon reference to the following description when taken in conjunction with the accompanying drawings wherein:

2

Figure 1 is a perspective view of the addressing machine master disclosed as this invention;

Figure 2 is a front elevational view of the addressing machine master as it is placed in the typewriter for the name and address to be typed upon the master duplicating paper;

Figure 3 is a side elevational view of the addressing master illustrated in Figure 2;

Figure 4 is a rear elevational view of the addressing master illustrated in Figures 2 and 3;

Figure 5 is a front elevational view of the addressing machine master when it is ready to be used in printing copy sheets;

Figure 6 is a side elevational view of the addressing master illustrated in Figure 5; and

Figure 7 is a rear elevational view of the addressing master illustrated in Figures 5 and 6 and showing the address thereon in reverse order for transfer to the copy sheets.

Returning now to the drawings, more particularly to Figure 1, wherein like reference symbols indicate the same parts throughout the various views, 10 indicates generally an addressing machine master constructed in accordance with this invention. The addressing machine 20 master 10 comprises a card 11 which may be of any suitable material such as cardboard, fiber board or the like. The card 11 has a front face 12 and a rear face 13.

A sheet of carbon paper 14 is positioned adjacent the front face 12 of the card. The carbon paper 14 has a carbon side 15 which is facing outwardly from the front face 12 of the card and is coated with a spirit duplicating composition. The carbon paper 14 may employ a duplicating material of the type ordinarily used in spirit duplicating carbon sheets which are obtainable in the market.

If desired, the duplicating material on the carbon paper 14 may comprise a suitable combination of waxes, oils and dyestuffs which is soluble in an alcoholic mixture upon repeated moistening so that portions thereof are transferred from the sheets in a manner which is familiar in the art. The carbon paper 14 has an opposite side 16 which may be lightly coated with an ordinary carbon composition such as used in typewriter carbon paper for making single copies.

A sheet of master duplicating paper 17 is positioned adjacent the rear face 13 of the card. The duplicating paper 17 may be of ordinary white bond paper or any other suitable type of paper. It is pointed out that the carbon paper and the master duplicating paper should be approximately the same width as the card 11, as shown in the drawing.

A metallic strip 18 is fitted along the top edge of a card 11 in such a manner as to clamp the carbon paper 14 and the duplicating paper 17 to the card 11 along the top edge thereof. The metallic strip 18 has ends 19 and 20 each of which project beyond the side edges of the card 11. The purpose of the metallic strip is to present a definite thickness so that the addressing machine masters can be fed from the magazine of the addressing machine one at a time. This strip 18 should be at the top of the card as this allows the typist to back the master into the typewriter. The feeding mechanism of the addressing machine may push against the ends 19 and 20 of the metallic strip 18 in order to feed the cards from the magazine. The metallic strips should be the first edge to leave the machine in order to prevent any snagging or buckling of the card.

In order to apply the dye to the addressing master 10, the duplicating sheet 17 is folded over in front of the carbon paper 14 in the manner illustrated in Figures 2 through 4. The addressing machine master 10 is then backed into a typewriter and an address as indicated at

21 is typed upon the master duplicating paper 17. When the address is typed on the duplicating paper a reverse impression is formed in the spirit duplicating composition on the inner surface of the duplicating paper 17. Since the carbon paper 14 is lightly coated with an ordinary carbon composition on the face adjacent the card 11 a direct reading impression will be made upon the front face 12 of the card.

The addressing machine master 10 is then removed from the typewriter and the sheet of duplicating paper 17 is then brought back to its original position. A gummed strip 22 is provided at the bottom of the duplicating paper 17 which, when moistened, will secure the lower end of the duplicating paper to the card 11. The sheet of carbon paper is then torn off as indicated in Figure 6 and a direct reading impression 23 is shown upon the front face of the card 11. The duplicating paper 17 is securely held in position with a reverse duplicating impression indicated at 24, facing outwardly, as illustrated in Figure 7. The result is a stiff cardboard paper master with the reverse duplicating impression on one side and a direct reading impression on the other side to facilitate the arrangement of the cards in the magazine or in the files.

The cards are then used to transfer the addresses to the copy in a manner well known to those familiar with the spirit duplication principle. Either the duplicating paper 17 or the copy sheets may be moistened with a suitable solvent.

Thus it can be seen that the addressing machine master of this invention is essentially a paper master which may be handled individually. The construction of the master is extremely simple and inexpensive. It is pointed out that the reverse impression cannot be made on the rear of the card merely by typing on the front face of the card since the stiffness of the card necessary to facilitate handling does not permit the reverse impression to be clearly reproduced. However, by employing a master sheet of duplicating paper in the manner disclosed in this invention, this difficulty is readily overcome and the result is a paper master which may be readily handled in addressing machines employing the spirit duplication principle.

It will be understood that this invention is susceptible to modification in order to adapt it to different usages and conditions, and, accordingly, it is desired to comprehend such modifications within this invention as may fall within the scope of the appended claims.

What is claimed is:

1. An addressing master comprising a card-like body portion, duplicating paper on one face thereof, carbon paper on the other face thereof with a coating of a spirit duplicating composition on the outwardly facing side, means attaching corresponding edges of said duplicating paper and said carbon paper to said body portion, and means for attaching the opposite edge of said duplicating paper to said body portion.

2. An addressing master comprising a card-like member, a sheet of duplicating paper adjacent one face of said member, a sheet of carbon paper adjacent the other

face thereof with the side away from said member having a coating of a spirit duplicating composition, and a light coating of ordinary carbon composition on the side facing said member, a metallic strip clamping the top edges of said duplicating paper and said carbon paper to the top edge of said member, and adhesive means on said duplicating paper for securing the lower edge thereof to said member.

3. An addressing master comprising a card-like body portion, duplicating paper on one face thereof, carbon paper on the other face thereof with a coating of spirit duplicating composition on the outwardly facing side, the other side of said carbon paper being lightly coated with an ordinary carbon composition, means attaching corresponding edges of said duplicating paper and said carbon paper to said body portion, and means for attaching the opposite edge of said duplicating paper to said body portion.

4. An addressing master comprising a card-like member, a sheet of duplicating paper facing one side of said member, a sheet of carbon paper adjacent to the other face thereof with the side away from said member having a coating of a spirit duplicating composition, there being a light coating of ordinary carbon composition on the other side of said carbon paper facing said member, a metallic strip clamping the top edges of said duplicating paper and said carbon paper to the top edge of said member, said metallic strip overhanging each side of said card-like member, and an adhesive means on said duplicating paper for securing the lower edge thereof to said card-like member.

5. In a method of making an addressing master comprising the steps of fastening the corresponding edges of a card-like body and a sheet of carbon paper with the side of the carbon paper having a spirit duplicating composition thereon facing outwardly of the card and the other side of the carbon paper being coated with an ordinary carbon composition, attaching a sheet of duplicating paper on the other side of a card-like body along the aforementioned edges thereof, flipping the duplicating paper over against the carbon paper, typing an address on the duplicating paper to transfer the address onto the card and to form a reverse image of the address from the spirit duplicating composition on the duplicating paper, flipping the duplicating paper back to its original position, and fastening the opposite edge of the duplicating paper to the card-like body whereby the reverse image will be facing outwardly and the address may be transferred to copy sheets.
